Inventor:
JACOB MERZ,
By
John H. Brumley,
His Attorney.

UNITED STATES PATENT OFFICE.

JACOB MERZ, OF CHICAGO, ILLINOIS, ASSIGNOR TO PERPETUAL AIR BAG COMPANY, OF CHICAGO, ILLINOIS, A CORPORATION OF ILLINOIS.

AIR BAG.

1,414,090.

Specification of Letters Patent. Patented Apr. 25, 1922.

Application filed September 11, 1920. Serial No. 409,608.

To all whom it may concern:

Be it known that I, JACOB MERZ, a citizen of the United States, and residing at Chicago, Illinois, have invented the new and 5 useful Improvement in Air Bags, of which the following is a specification.

This invention relates to air bags such as are used in repairing pneumatic tires to support the tire during the vulcanizing process. This invention constitutes an improvement on the device described in my application Serial No. 269,708, filed January 4, 1919.

Air bags of this character are inflated for 15 use by means of compressed air, steam or the like. In either case water or other liquid may be carried into the bag by the inflating medium. When the bag is inflated with air, water or oil which are sometimes present in 20 the piping system may be carried into the bag from the outside. When inflated with steam, a certain amount of condensation takes place and the water so formed collects in the bag. Under any of these circumstances 25 the collection of such liquids in the bag is the cause of deterioration of the bag which in time will rot at such points at which the liquid collects.

One of the objects of this invention, therefore, is to provide an air bag which may be drained so as to prevent the collection of such liquids and consequent deterioration.

Further objects will appear from the detail description taken in connection with 35 the accompanying drawing, in which:

Figure 1 is a sectional view showing an air bag embodying this invention;

Figure 2 is a section on line 2—2 of Figure 1;

Figure 3 is a partial sectional view showing the application of this invention to a modified form of air bag; and

Figure 4 is a section on line 4—4 of Figure 3.

Referring now to the accompanying drawing, 45 1 designates a support, which may be in the form of an iron rod which is preferably curved to approximately the average radius of the tire to be repaired. The ends of the 50 rod 1 may be threaded to engage a pair of frusto-conical heads 3 and 4. Each of said heads is provided with an annular depression or groove 2 on the interior side thereof. The heads 3 and 4 are also equipped 55 with shanks 5 and 6 each being bored length-

wise thereof to provide a duct 21 through which the inflating medium may be introduced. The duct 21 communicates by means of a plurality of inclined ducts 20 with the bottom of the annular groove 2.

The air bag proper may consist of one or more concentric tubes of elastic material such as rubber 9, which may be covered with a protective covering of canvas or similar fabric or knitted material 10. The ends of the bag are adapted to slip over the conical faces of the heads 3 and 4 with a snug fit. A metal, cup shaped cap 11 having conical sides adapted to fit the conical faces of the heads 3 and 4, and having an aperture 70 through which the shanks 5 and 6 may pass, is fitted over each of said heads 3 and 4 so as to confine the walls of the bag between the conical face of the head on the inside and the conical face of the cap 11 on the outside to 75 clamp said bag firmly between said faces. A nut 12 threaded to engage a corresponding thread on each of said shanks 5 and 6 may be screwed down upon the cap 11 so as to firmly clamp the bag.

In the embodiment shown in Figures 3 and 4, the bag is constructed of a layer of fabric 16 embedded between interior and exterior coverings of rubber or similar material 15.

In use, the inflating medium may be conveyed to the bag by means of suitable connections such as 7. The lower end of the bag may be sealed by means of a cap screwed on the shank 6, or a connection similar to 90 the connection 7 may be attached to the lower end and the inflating medium may be caused to circulate through the bag. In either case, the bag being used preferably in a vertical position, any liquid introduced into the bag 95 will collect in the space 2 from which it may be drained through the ducts 20 and 21. In case the bag is sealed at the lower end, such drainage may be accomplished by simply opening the seal. In the case where the inflating medium circulates through the bag such drainage will take place of its own accord and may be assisted by setting up circulation in such a way that the liquids to be removed will be carried out with the circulating medium.

It is obvious that various changes may be made in the details of construction without departing from the spirit of this invention; it is, therefore, to be understood that this in- 110

vention is not to be limited to the specific details shown and described.

Having thus described this invention, what is claimed is:

- 5 1. In a device of the character described, an inflatable bag, means for inflating said bag, and an end cap adapted for draining said bag.
- 10 2. In a device of the character described, an inflatable bag, means for inflating said bag adapted to permit circulation of the inflating medium, and means at one end thereof for draining the bag.
- 15 3. In a device of the character described, an inflatable bag, means for inflating said bag adapted to permit circulation of the inflating medium, and means at one end thereof for draining said bag.
- 20 4. In a device of the character described, an inflatable bag, means for inflating said

bag adapted to permit circulation of the inflating medium, and means for draining said bag in the direction of circulation of said medium.

5. In a device of the character described, 25 an inflatable bag, means for inflating said bag, and means for draining said bag comprising a head, provided with collecting space for liquids; and a duct connecting said space with the exterior of the bag. 30

6. In a device of the character described, an inflatable bag, means for inflating said bag, and means for draining said bag comprising a clamping head, provided with an annular groove forming a collecting space 35 for liquids, and a duct connecting said space with the exterior of the bag.

In testimony whereof I affix my signature this 31st day of July, 1920.

JACOB MERZ.
